Primary Examiner — Cary M Robinson*Assistant Examiner* — Adam C Mager(74) *Attorney, Agent, or Firm* — Temmerman Law; Mathew J. Temmerman(57) **CLAIM**

I claim the ornamental design for a vehicle steering linkage component, as shown and described.

DESCRIPTION

FIG. 1 is an upper perspective view of a vehicle steering linkage component, showing my new design;

FIG. 2 is a right side view thereof;

FIG. 3 is a front side view thereof;

FIG. 4 is a left side view thereof;

FIG. 5 is a top side view thereof;

FIG. 6 is a back view thereof;

FIG. 7 is a bottom view thereof; and,

FIG. 8 is a lower perspective view thereof.

1 Claim, 4 Drawing Sheets---
